UNITED STATES PATENT OFFICE.

ERNEST H. ROSS, OF IOWA CITY, IOWA.

DESIGN FOR A WALKING CANE.

Application filed July 6, 1925. Serial No. 14,005. Term of patent 14 years.

To all whom it may concern:

Be it known that I, ERNEST H. ROSS, a citizen of the United States of America, residing at Iowa City, in the county of Johnson and State of Iowa, have invented a new, original, and ornamental Design for Walking Canes, of which the following is a specification, reference being had to the accompanying drawing, forming a part thereof.

The figure is a front elevational view of the walking cane, showing my new design.

I claim:

The ornamental design for a walking cane, as shown.

ERNEST H. ROSS.
